UNITED STATES PATENT OFFICE.

OSCAR LASCHE, OF CHARLOTTENBURG, GERMANY, ASSIGNOR TO GENERAL ELECTRIC COMPANY, A CORPORATION OF NEW YORK.

WHEEL FOR ELASTIC-FLUID TURBINES.

1,118,361.

Specification of Letters Patent.

Patented Nov. 24, 1914.

Application filed June 19, 1914. Serial No. 846,149.

To all whom it may concern:

Be it known that I, OSCAR LASCHE, a subject of the Emperor of Germany, residing at Charlottenburg, Germany, have invented 5 certain new and useful Improvements in Wheels for Elastic-Fluid Turbines, of which the following is a specification.

The present invention relates to bucket or vane wheels for elastic-fluid turbines, and 10 particularly to those having a plurality of rows of buckets or vanes.

The object of the invention is to provide a structure which can be constructed at a low cost, which can be readily assembled, 15 and which, while using and embodying the advantages of the undercut groove for holding the buckets, avoids the difficulties in constructing and assembling which have heretofore been met with.

20 For a consideration of what I believe to be novel and my invention, attention is directed to the following specification and to the claims appended thereto.

In the accompanying drawing, Figures 1 25 to 4 illustrate in section four forms which my invention may take, a three row combination being illustrated in each instance.

In carrying out my invention I form the bucket or vane carrying wheel of a plurality 30 of disks in the sides of which adjacent the peripheries are formed annular grooves or slots. These grooves or slots are so formed that when the disks are assembled side by side they coöperate to form undercut slots 35 for the reception of the bucket or vane bases. Owing to this construction the grooves can be much more easily formed. For example, they can be formed by turning in a lathe. The assembling of the bucket bases in the 40 wheel is also much more simple as the buckets and the usual spacing pieces can be inserted before the disks are assembled and fastened together. This avoids the use of the usual lateral openings through which 45 the bucket bases are inserted into the groove and also the use of special locking buckets.

In the drawing the arrangement shown in each of the figures is broadly the same and the same reference numerals will accordingly be used for corresponding parts.

50 Referring to the figures of the drawing, 5 is the rotor shaft which carries the bucket wheel. In the examples illustrated three row or ring bucket wheel combinations are

shown each comprising the intermediate 55 disk members 6 and 7 and the outer disk members 8 and 9. It will be understood, however, that other than three ring combinations may be constructed.

In Fig. 1 the members 6 and 7 are shown 60 as flat disks of uniform thickness extending down to the shaft and provided on both sides with annular grooves 10 and upon the outer side with grooves 11. The outer members 8 and 9 are in the form of annular rings and 65 have grooves 12 and annular projections 13. When assembled the grooves 10 coöperate with each other and with grooves 12 to form the undercut slots for the reception of the bases of the buckets 14. The projections 13 enter the grooves 11 to form a rigid structure when assembled. The wheel is shown as fastened to the shaft by means of the tapered sleeves 15 and nuts 16. The disks 6, 7, 8 and 9 may be fastened firmly together by 70 means of suitably spaced rivets or bolts 17. The specific arrangement shown in Fig. 1 has the advantage that the disk members 6 and 7 may be formed from rolled stock and require little machine work. The members 80 8 and 9 are formed as annular rings in order to lighten the structure of the wheel as a 75 whole.

In the arrangement shown in Fig. 2, both the intermediate and outer disk members extend 85 down to the shaft and the same are formed with thick bases 18 and thinner web portions 19 to lighten the structure. These web portions terminate at their peripheries in thickened projections 20 which coöperate 90 to form the undercut grooves for holding the buckets.

The arrangement of Fig. 3 is similar to that of Fig. 2 in that each of the disk members extend down to the shaft. In this figure the members 6 and 7 are formed on one side with flat coöoperating faces as indicated at 21, which permit of a somewhat lighter structure, as will be obvious. The undercut slots are also of a somewhat different design. 100

The arrangement of Fig. 4 is quite similar to that of Fig. 2 differing therefrom mainly in the specific form of the undercut slots and by the provision of a spacing ring or member 22 between the intermediate members 6 and 7.

In Figs. 3 and 4 is illustrated an alternative method of fastening the disks of the

wheel to each other and the wheel to the shaft, the disks being fastened together by means of rivets or bolts 23 located adjacent the shaft and shrunk and keyed to the shaft 5 as indicated at 24.

In connection with each of the structures illustrated, it will be clear that the grooves for forming the undercut slots can be readily formed as already set forth and that 10 buckets can be readily inserted in place and the wheel assembled. The buckets or vanes may be provided with covers 25 at their outer ends if desired.

In accordance with the provisions of the 15 patent statutes, I have described the principle of operation of my invention, together with the apparatus which I now consider to represent the best embodiment thereof; but I desire to have it understood that the apparatus shown is only illustrative, and that the 20 invention can be carried out by other means.

What I claim as new and desire to secure by Letters Patent of the United States, is,—

1. A turbine rotor comprising a plurality 25 of intermediate disk members having grooves in their opposite faces adjacent their peripheries, two outer disk members each having a groove in one face and a plurality of rings of buckets held between said disks 30 with their bases seated in the grooves.

2. In a turbine, a bucket wheel comprising intermediate and outer disk members, the peripheries of which are spaced apart, 35 grooves formed in the adjacent faces of said members to form undercut slots, buckets held between said disk members with their

bases in the undercut slots, and means for fastening said disk members together.

3. In a turbine, a shaft, a bucket wheel comprising a plurality of intermediate and 40 outer disk members which extend down to the shaft and have grooves formed adjacent their peripheries which co-operate to form undercut slots, buckets held between said members with their bases in 45 said grooves, means for fastening said disk members together, and means for fastening the wheel to the shaft.

4. In a turbine, a shaft, a bucket wheel comprising intermediate and outer disk 50 members having grooves formed adjacent their peripheries which co-operate to form undercut slots, buckets held between said members with their bases in said slots, holding means adjacent the shaft for fastening 55 said disks together, and means for fastening the wheel to the shaft.

5. In a turbine, a shaft, a bucket wheel comprising intermediate and outer disk members which extend down to the shaft 60 and have grooves formed adjacent their peripheries, which grooves co-operate to form undercut slots when the disk members are assembled, and buckets held between said members with their bases in said grooves. 65

In witness whereof, I have hereunto set my hand this fourth day of June, 1914.

OSCAR LASCHE.
